SPRAY HEADS

CROSS-REFERENCE TO RELATED PATENT APPLICATIONS

This application is a U.S. National Stage of International Application No. PCT/GB2017/050643, filed Mar. 10, 2017, which claims priority to and the benefit of United Kingdom Patent Application 1607824.8, filed May 4, 2016, each of which is incorporated herein by reference in its entirety.

BACKGROUND

This invention relates to spray head and more especially to adjustable spray heads for use in a shower.

Prior art adjustable spray heads often have an aperture spray plate rotatable on the body of the spray head to change the spray pattern of water flowing from the apertures in the spray plate. These spray heads can be difficult to use, especially for elderly or disabled users with reduced manual dexterity and/or eyesight.

There is therefore a need for a spray head which provides improved ease of adjustment.

SUMMARY

According to one aspect the present invention provides a spray head for a shower comprising a spray plate having an apertured portion and an actuator portion, the apertured portion having apertures therein and the actuator portion being configured to be depressed by a user to change a spray pattern provided by the apertures of the apertured portion.

The spray head may be part of a shower handset, or may be a fixed ceiling- or wall-mounted shower head.

It may be that the actuator portion is configured to operate a spray control mechanism located behind the spray plate to control fluid flow to the apertured portion for changing the spray pattern.

It may be that the spray control mechanism includes a flow plate located behind the spray plate and having holes therein aligned with the apertures in the apertured portion of the spray plate.

It may be that the spray control mechanism is configured to be activated by depression of the actuator portion of the spray plate.

It may be that the spray control mechanism includes a diverter operable in response to depression of the actuator portion of the spray plate to change the spray pattern.

It may be that the actuator portion is integral with, the apertured portion of the spray plate.

It may be that the spray plate is made of a flexible material.

It may be that the actuator portion is arranged to allow switching of the spray pattern each time the actuator portion is depressed.

According to another aspect, the invention provides a method of adjusting the spray pattern of fluid from a spray head comprising a spray plate having an apertured portion and a depressible actuator portion, the method comprising depressing the depressible actuator portion of the spray plate.

BRIEF DESCRIPTION OF THE DRAWINGS

There now follows by way of example only a detailed description of embodiments of the present invention with reference to the accompanying drawings in which:

2

FIG. 1 shows a front view of a shower handset according to an embodiment;

FIG. 2 shows a side view of the shower handset of FIG. 1; and

FIG. 3 shows an exploded view of the shower handset of FIGS. 1 and 2.

DETAILED DESCRIPTION

10 Referring to the drawings, a shower handset **100** is shown. The shower handset **100** comprises a hollow body **110** having a grip portion **110a** and a head portion **110b** and a spray assembly **120**. In this embodiment, the spray assembly **120** has a stem portion **120a** and a spray portion **120b**. The stem portion **120** is received within the grip portion **110a** of the body **110** and has a connector **122** at a first end that extends from the grip portion **110a** and has a thread **122a** for attaching a water supply such as a flexible hose (not shown). The spray portion **120b** is provided at a second end of the stem portion **120a** and is located in the head portion **110b** of the body **110**. The stem portion **120a** delivers water to the spray portion **120b**. In other embodiments (not shown), the stem portion **120a** may be omitted and the grip portion **110a** 15 may be connected to the water supply and deliver water to the spray portion **120b**.

The spray portion **120b** includes a spray plate **124** having an apertured portion **124a** and an actuator portion **124b**. The apertured portion **124a** has a plurality of apertures **126** which define at least two spray patterns.

The spray portion **120b** further includes a spray control mechanism **128** located behind the spray plate **124** and operable by the actuator portion **124b** to control selectively the supply of water to the apertures **126** in the spray plate **124**.

The spray control mechanism **128** includes a flow plate **130** and a switch member **132**. The switch member **132** is pivotally connected to the flow plate **130**. The spray plate **124** overlies and conceals the flow plate **130** and switch member **132**.

40 The flow plate **130** has a plurality of holes **134** aligned with the apertures **126** in the spray plate **124**. The spray plate **124** and flow plate **130** are configured to confine fluid flow 45 through each hole **134** to the aligned aperture **126** and prevent fluid leaking between the spray plate **124** and flow plate **130**. For example, the spray plate **124** and flow plate **130** may be configured to seal around each hole **134** and aligned aperture **126**.

50 In this embodiment, the apertures **126** in the spray plate **124** and holes **134** in the flow plate **130** include a central aperture **126a/holes 134a** to provide a first spray pattern, an inner array of apertures **126b/holes 134b** surrounding the central aperture **126a/holes 134a** to provide a second spray 55 pattern, an intermediate array of apertures **126c/holes 134c** surrounding the inner array to provide a third spray pattern, and an outer array of apertures **126d/holes 134d** surrounding the intermediate array to provide a fourth spray pattern. The central hole **134a** in the flow plate **130** may be provided with a mesh to produce a fine spray pattern.

60 The number, shape and configuration of the apertures **126/holes 134** may be changed to provide any number and/or combination, of spray patterns in other embodiments. Different spray patterns may use entirely separate sets of apertures **126/holes 134**. Alternatively, the same apertures **126/holes 134** may be used for more than one spray pattern. For example, in some embodiments, fluid flow through the

central aperture 126a/134a may be present in all spray patterns, and/or one spray pattern may use all apertures 126/holes 134.

The actuator portion 124b is located on the circumference of the spray plate 124 and forms a curved protrusion therefrom. The actuator portion 124b may be aligned with the grip portion 110a of the body 110. This may facilitate location of the actuator portion 124b by a user with impaired vision. Alternatively or additionally, the surface of the spray plate 124 may have a different texture in the region of the actuator portion 124b to facilitate its location by a user.

The actuator portion 124b overlies the switch member 132 and is configured to project from the body 110 in its inactive position as best shown in FIG. 2. in use the actuator portion 124b is depressible by a user from its inactive position to an active-position to operate the spray control mechanism via the switch member 132 to change the spray pattern. The switch member 132 may be biased by a spring (not shown) to return the actuator portion 124b to its inactive position when released by the user. Each depression of the actuator portion 124b changes the spray pattern.

The flow plate 130 may comprise channels (not shown) between the back of the flow plate 130 and the head portion 110b of the body 110 that direct flow of water to the holes 134 in the flow plate 130 and the spray control mechanism may comprise a diverter (not shown) operable by the switch member 132 to control the water flow to the channels to change the selected spray pattern or spray patterns in response to activation of the actuator portion 124b.

The spray plate 124 may be flexible. The spray plate 124 may comprise a unitary component. The apertured portion 124a and actuator portion 124b may be integral. The spray plate 124 may be configured to allow the actuator portion 124b to be moved relative to the apertured portion 124a. The actuator portion 124b may be connected to the aperture portion 124a by an integral hinge portion 124c of the spray plate 124.

The flow plate 130 may be rigid. The flow plate 130 may be fixed relative to the head portion 110b of the body 110. The apertured portion 124a of the spray plate 124 may be supported by the flow plate 130. The apertured portion 124a may be fixed relative to the head portion 110b of the body 110.

The invention is not limited to the embodiment described. The spray control mechanism responsive to depression of the actuator portion may be of any suitable construction. The spray plate may be provided with more than one actuator portion.

The invention claimed is:

1. A spray head for a shower comprising a spray plate having an apertured portion and an actuator portion, wherein the actuator portion of the spray plate is connected to the apertured portion of the spray plate by an integral hinge portion of the spray plate, the apertured portion having apertures therein and the actuator portion being configured to be depressed by a user to change a spray pattern provided by the apertures of the apertured portion; and

a spray control mechanism comprising a flow plate and a switch member pivotally connected to the flow plate, wherein the spray plate overlies the flow plate and the switch member, wherein depression of the actuator portion operates the spray control mechanism via the switch member.

5 2. The spray head of claim 1, wherein the actuator portion is arranged to operate the spray control mechanism located behind the spray plate to control fluid flow to the apertured portion for changing the spray pattern.

10 3. The spray head of claim 1, wherein the flow plate is located behind the spray plate and has holes therein aligned with the apertures in the apertured portion of the spray plate.

15 4. The spray head of claim 1, wherein the spray control mechanism includes a diverter operable in response to depression of the actuator portion of the spray plate to change the spray pattern.

20 5. The spray head of claim 1, wherein the actuator portion is integral with the apertured portion of the spray plate, such that the spray plate is provided by a unitary component.

25 6. The spray head of claim 5, wherein the spray plate is made of a flexible material.

7. The spray head of claim 1, wherein the actuator portion is arranged to allow switching of the spray pattern each time the actuator portion is depressed.

25 8. The spray head of claim 1, wherein the flow plate is rigid.

9. The spray head of claim 1, wherein the switch member is biased, by a spring, to return the actuator portion to its inactive position.

30 10. The spray head of claim 1, wherein the spray plate and the flow plate are configured to confine fluid flow through the apertures such that fluid is prevented from leaking between the spray plate and the flow plate.

11. The spray head of claim 1, wherein the switch member is pivotally connected to the flow plate by a hinge.

12. A shower comprising the spray head of claim 1.

13. A method of adjusting the spray pattern of fluid from a spray head according to claim 1, the method comprising depressing the depressible actuator portion of the spray plate.

35 14. A spray head for a shower comprising:
a spray plate having an apertured portion and an actuator portion, the apertured portion having apertures therein and the actuator portion being configured to be depressed by a user to change a spray pattern provided by the apertures of the apertured portion; and
a spray control mechanism comprising a flow plate and a switch member pivotally connected to the flow plate, wherein the spray plate overlies the flow plate and the switch member, wherein depression of the actuator portion operates the spray control mechanism via the switch member;

40 wherein the apertured portion of the spray plate is circular, and wherein the actuator portion of the spray plate is provided as a curved protrusion from a circumference of the aperture portion.
